APPARATUS FOR DEPOSITING STRIPS OF
ADHESIVE UPON A BASE MATERIAL

Thomas O. Bretherton, Villanova, Pa.

Application July 29, 1948, Serial No. 41,286

4 Claims. (Cl. 91—12)

1

This invention relates to new and useful improvements in apparatus for depositing one or more strips of adhesive upon a base material, and is particularly concerned with apparatus that is especially adapted for use in connection with the manufacture of pile fibre surfaced slide channel sections for the glass panes of automobile doors and windows.

As is well-known, the channels and strips associated with the glass panes of automobile windows and doors usually are lined or surfaced with felt or the like which serves principally to prevent rattling of the glass in the frame and at the same time provides a cushion between the glass panes and the supporting structure of the doors and windows so that breaking of the glass in ordinary usage of the vehicle is substantially eliminated.

The manufacture of these channel and strip sections presents a problem in the automobile industry principally because of the materials and labor cost involved in producing an item which when finished constitutes only a very small part of a complete automobile. For example, one method of producing these channels which is used extensively in the automotive industry consists in securing by means of stitching or adhesive three relatively narrow strips of felt in closely spaced parallel relation upon a suitable backing fabric such as light canvas or sized cotton and this fabric material with the felt strips secured thereon is then adhesively secured upon the surface of a flat strip of metal. This metal strip with the felt carrying backing fabric secured thereto is then formed into a generally U-shaped channel with the fabric covered surface of the strip residing interiorly of the channel so that the three felt strips thereon overlie the inner surfaces of the bottom and opposite side wall portions of the channel.

It will be noted that the described method of producing these channel sections involves a number of separate and distinct steps which, in addition to the cost of extra materials, consumes considerable time and labor which makes the cost of manufacturing these channels and strips substantially out of proportion for such a small part of a complete automobile.

With the foregoing in mind, the principal object of the present invention is to provide a novel apparatus for depositing one or more strips of adhesive upon a continuous moving base material in the manufacture of pile fibre surfaced articles as set forth.

This and other objects of the invention and

2

the various features and details of the construction and operation thereof are hereinafter fully set forth and described with reference to the accompanying drawings in which:

5 Fig. 1 is a side elevational view of one form of apparatus suitable for the manufacture of articles according to the present invention;

Fig. 2 is an enlarged sectional view taken on line 2—2, Fig. 1;

10 Fig. 3 is a fragmentary longitudinal sectional view of the apparatus shown in Fig. 1;

Fig. 4 is an enlarged sectional view of a portion of the apparatus appearing in Fig. 3 and more particularly as viewed on the line 4—4, Fig. 6;

15 Fig. 5 is a detached view in perspective of one of the members of the adhesive feed mechanism shown in Fig. 4;

Fig. 6 is a transverse sectional view taken on the line 6—6, Fig. 1;

20 Fig. 7 is a partial transverse section as viewed on the line 7—7, Fig. 8;

Fig. 8 is a sectional plan as viewed on the line 8—8, Fig. 6;

25 Fig. 9 is a perspective view of the section of a length of the base strip material with three strips of the adhesive deposited thereon.

Fig. 10 is a view similar to Fig. 9 showing the same strip after the fibres have been deposited thereon in substantially perpendicular relation;

30 Fig. 11 is an enlarged view in perspective of a length of one of the strips after being severed longitudinally of the length of the material shown in Fig. 10; and

Fig. 12 is a sectional view showing the strip of 35 Fig. 11 after it has been formed into channel section for use in guiding and supporting the glass panes of automobile windows and doors.

Referring now more particularly to the drawings, the present invention contemplates passing 40 a strip of material such as metal, fabric, or the like, continuously through a novel adhesive applying device which operates to apply upon the surface of the moving strip one or more continuous bands of adhesive predetermined width

45 preparatory to passing the strip of material with the band or bands of adhesive thereon through apparatus which is constructed and operable to deposit onto the continuously moving strip relatively short textile fibres of wool or the like while simultaneously vibrating said strip to cause the fibres to adhere to the adhesive banded areas of

50 the strip in generally perpendicular relation to the surface of the latter. The strip with the pile fibre surface adhesively secured thereto is then passed through a chamber maintained at an

elevated temperature to dry, cure or vulcanize the adhesive as the case may require.

One form of apparatus for producing strip material as described is shown in the accompanying drawings. The apparatus illustrated is constructed upon a framework comprising four upright members or standards 1 to which are secured a pair of transversely extending horizontally disposed channel members 2 that in turn support a pair of relatively spaced parallel longitudinally extending channel members 3. Mounted on the extreme outboard ends of the longitudinal channels 3 are drag and draw devices 10 and 11, respectively, for moving a length of base material M through the machine under proper conditions of tension.

The draw device 11, shown at the righthand side of Fig. 1 of the drawings, comprises a pair of relatively opposed rolls 12 and 13 between which the length of base material is adapted to pass. The bottom roll 13 is driven at a predetermined rate of speed from a suitable motor 14 through a belt drive 15 and the upper roller 12 is biased by spring 16 toward the driven lower roll 13.

On the other hand the drag device 10, shown at the extreme left of Fig. 1, comprises a lower idler roll 17 and an upper roll 18 between which the strip of base material M passes, and the upper roll 18 is biased by a spring 19 toward the lower roll 17 and into contact with the strip of material. The pressure of the spring 19 acting on the roll 18 may be regulated by the adjustment of a screw 20 to cause the rolls 17 and 18 to grip the strip of base material passing therebetween with the desired force with respect to the pull exerted by the draw device 11 so that portion of the length of the base material M lying between these drag and draw devices 10 and 11 will be under a predetermined degree of tension.

After passing through the drag device 10, the strip of base material M passes through an adhesive applying device which is generally designated by the numeral 21 and constructed as more particularly shown in Figs. 4 to 8, inclusive, of the drawings. As there shown, the adhesive applying device comprises one or more adhesive troughs or receptacles 23, depending upon the number of strips or bands of adhesive to be applied to the surface of the strip M and, in similar manner, the width of the particular receptacles 23 will be determined by the width of the band or bands of adhesive material to be deposited thereby onto the surface of said strip. The adhesive receptacles 23 constructed as shown in Figs. 4 and 5 of the drawings include relatively spaced parallel side wall portions 24 and a declining, concave intermediate wall portion 25 which has its lower terminal edge 26 spaced inwardly with respect to the front face edges of the receptacle side wall portions 24. (See Fig. 5.)

During passage of the strip of base strip M through the adhesive applying device 21 the strip rests upon a plate or platen 27 which is secured to the upper surface of an underlying transverse channel member 28 that is secured, for example, by bolts 29 to the underside of a bridge member 30. The bridge member 30 is of generally inverted flat U shape and is secured by bolts or the like 31 to the longitudinally extending channels 3 of the main frame, for example, in the relation shown in Fig. 6 of the drawings.

Provided at the upper rearward edge portion of the adhesive receptacle 23 is an outwardly directed flange portion 32 which is undercut to

provide a groove 33, and said receptacles are supported in closely overlying relation with respect to the upper surface of the continuously moving base strip M by engaging said flange 32 over the upper projecting edge portion 34 of a support bracket 35 so that said edge 34 engages in said groove 33 as shown in Fig. 4. The bracket 35 extends cross-wise of the moving strip M and is slidably supported upon screws or the like 36 which pass therethrough and are threaded into tapped holes provided in suitable bosses 37 provided on the outer face of the bridge member 30, for example, as shown in Fig. 8 of the drawings.

Expansion springs 38 are positioned intermediate the enlarged head portion of each screw 36 and the adjacent face of the bracket 35 thereby continuously urging the latter and the adhesive receptacles 23 supported thereby in an inward direction or to the right with respect to Fig. 4 so that the front or inner edges of the receptacle side walls 24 normally are maintained in firm abutting relation against the outer face of a doctor blade 39 which is carried by the bridge member 30 cross-wise of the moving base strip M.

The doctor blade 39 cooperates with the receptacle side walls 24 and the inner terminal edge 26 of its concave wall 25 to define an opening for the passage of adhesive from the receptacle 23 on to the upper surface of the continuously moving base strip M. In order to control and regulate the thickness of the band or bands of adhesive deposited onto the base strip M from the receptacles 23, the doctor blade 39 is vertically adjustable. As shown in Fig. 7 this is accomplished in the present instance by providing in the bridge member 30 an adjusting screw 40 having axially spaced reversely threaded portions 41 and 42 which operate, upon turning of said screw by the knob 43, to effect axial displacement of nut members 44 and 45 respectively, thereon, and displacement of these nut members works through the medium of associated bell crank levers 46 and 47 to effect vertical positioning of the doctor blade 39 in micrometer adjustments with comparative accuracy.

The adhesive material may be supplied to the receptacle 23 and maintained at a constant lever therein by conducting the adhesive material from a suitable source of supply 48 through a hose or other suitable connection 49 to a manifold 50 from which separate connections 51 lead through valves 52 and pipes 53 to the individual receptacles 23, for example, as clearly shown in Figs. 4 and 6 of the drawings. The valves 52 may be adjustably supported above the bridge member 30 by means of a bracket 54 secured thereto and having a slot 55 therein whereby the valves may be transversely positioned within the limits of the slot with respect to the base strip M. It will be understood of course that the number of receptacles 23 provided in any given case, as well as the respective widths thereof, will be governed entirely by the number of bands of adhesives it is desired to place upon the surface of the base strip and the width of such bands.

The particular adhesive material employed preferably is a synthetic rubber adhesive which is water-proof and resistant to cleaning and other solvents. A number of good adhesives having these properties are available on the market. The thickness of the band of the adhesive deposited upon the upper surface of the base material will vary widely depending upon both the type and length of fibres employed as well as upon the viscosity and solids content of the ad-

hesive composition and in each case may best be determined by trial and error with respect to these factors.

The strip material emerging from passage through the adhesive device 21 illustrated in the drawings will have deposited thereon three continuous bands of the adhesive arranged in spaced parallel relation extending longitudinally of the base strip M, for example, as shown in Fig. 9 of the drawings.

The strip M with the adhesive bands thereon next passes through an elongated chamber 60 in the course of travel through which uniform relatively short length fibres such as, for example, wool or other material are deposited by gravity onto the adhesive banded strip while the latter, which is maintained under tension provided by the drag and draw devices 10 and 11, respectively, is vibrated. In the present instance vibration of the continuously moving base strip is accomplished by causing the strip to pass over a plurality of transversely arranged polygonal shafts 61 of polygonal cross-section shape as shown in Fig. 4. The opposite ends of these shafts are rotationally supported in suitable journal boxes 62 and 63, respectively, mounted exteriorly of the chamber 60. The shafts 61 are driven from a motor 64 through a belt drive 65 to one of said shafts 61 and from the latter the other shafts are driven by connecting belts 66, 66 through pulleys 67 fixed on each of the shafts. It is to be noted that the rotational axes of the vibrator shafts 61 do not all lie in the same horizontal plane and that the rotational axes of the second and fourth shafts are spaced respectively slightly above and below the plane of the rotational axes of the first and third of said shafts thereby causing each shaft 61 to be effective individually to vibrate the base strip M.

The chamber 60 is mounted in the rectangular area defined by the four uprights or standards 4 of the apparatus framework, and overlying the chamber 60 is a hopper 68 which extends the full length of the chamber 60 and has relatively vertical upper side wall portions 69 which terminate toward the bottom of the hopper in inwardly curving wall portions 70 which provide, in conjunction with a transversely arcuate screen 71 in the opening to the chamber 60 a rounded bottom to the hopper. The opening from the hopper to the underlying chamber 60 extends substantially the full length and width of the latter and the screen 71, which is of predetermined size mesh, bridges the opening between the hopper and the chamber 60 and is curved to the same radius as the lower side wall portions 70 of the hopper 68 as shown in Fig. 2 of the drawings.

Rotatably mounted within the hopper about horizontal axis extending longitudinally thereof is a generally cylindrical agitator comprising a central shaft 72 having a plurality of spiders 73 secured thereon and provided with circular rim portions 74 to which are secured support strips 75 that extend longitudinally of the agitator and are provided with a slight spiral rake, for example, as shown in Fig. 1 of the drawings. Secured to each of these support strips 75 is a backing strip 76 having metal pins or relatively stiff nylon bristles 77 projecting radially therefrom in the relation shown in Fig. 2 of the drawings. Similarly provided in the curved bottom portions 70 of the hopper 68 along opposite sides of the opening therein to the chamber 60 are stationary backing members 78 of relatively greater width than the strips 75 and having pro-

jecting therefrom radially with respect to the center of the agitator, pins or relatively stiff bristles 79. The construction and arrangement of the agitator and stationary pins is such that the tips of the agitator pins have relatively close clearance with the stationary pins but do not actually top them.

One of the difficulties encountered in the handling of short textile fibres of lengths say from about $\frac{1}{2}$ inch to about $\frac{3}{8}$ inch is the tendency for these fibres to "wad" and collect into rolls and balls which build up to substantial size and eventually clog the machine, and by providing the agitator described with its pins or bristles arranged to just clear the stationary pins or bristles 79, it has been found that any accumulations of fibres tending to form rolls or balls are subjected immediately to what might be termed a light carding action which effectively eliminates any tendency of the short fibres to form into objectionable rolls or balls.

The fibres are admitted to the hopper 68 through an opening in the top thereof and are discharged onto a baffle 80 which tapers endwise of the hopper from its mid-point and has laterally sloping sides which cooperate with the endwise taper thereof to insure a substantially uniform distribution of the fibres longitudinally of the hopper. The fibres discharge from the hopper 68 through its bottom opening and the screen 71 onto the adhesive banded strip of base material M. The fibres which are deposited onto the adhesive banded areas of the base strip M adhere to the latter and due to the vibration imparted to the tensioned base strip M by the polygonal shafts 61, the fibres deposited onto the adhesive band or bands of the strip have one end embedded in the adhesive and extend substantially perpendicular to the plane of the base strip surface thus forming thereon a unique pile fibre surface simulative of the effect provided by certain pile fabrics such as carpets and the like.

The fibres deposited onto the base strip M which do not become embedded in the bands of adhesive are discharged from opposite sides of the strip by the vibrations imparted thereto and drop into a downwardly tapering bin portion 81 provided in the lower part of the chamber 60. The fibres discharged into the bin 81 are withdrawn therefrom and through a duct 82 by a fan or blower 83 which in turn discharges the fibres through another duct 84 and returns them to the hopper 68. In the illustrated embodiment of the invention the fan or blower 83 is driven by the motor 64.

After the fibres have been deposited onto the adhesive banded areas of the base strip M as described, the latter emerges from the chamber 60, passes through the draw device 11 previously described, and then is passed through a drying or curing chamber (not shown) of any suitable type which is maintained at the desired temperature to effect drying, curing or vulcanization of the adhesive material as may be required to effect a permanent bond of the fibres to the base strip M and with the illustrated form of apparatus to provide a pile fibre banded strip of the construction shown in Fig. 11 of the drawings. Whether or not the adhesive material should be merely dried or cured or, for example, vulcanized, will depend to a large extent upon the type of adhesive material employed and also upon the particular use which is to be made of the pile fibre surfaced strip product. Thus in the case of guide 70 channels and strips for the glass panes of auto-

mobile windows and doors where their use is accompanied by substantial wear and exposure to substantially the entire range of weather conditions and cleaning solvents, an exceedingly tough and durable bonding of the fibres to the base strip is essential and therefore an adhesive of the synthetic rubber type preferably is employed and properly cured or vulcanized by subjecting the pile fibre surfaced strip to the required heat treatment for a predetermined period of time.

The multiple-banded strip shown in Fig. 10 is split or cut longitudinally thereof along the broken lines *a*, to produce three ribbons *M'* of the construction shown in Fig. 11 of the drawings. These single ribbons *M'* may be used flat or may be run through a suitable machine to form them into lengths of channel cross-section shape with the pile fibre surface thereon disposed interiorly of the channel as shown in Fig. 12 of the drawings. If desired, the free edge portions of the channel sections being turned outwardly and providing beads along the opposite side edges thereof substantially as shown.

By way of illustration, a good product may be produced by advancing the base strip *M* through the apparatus at a linear speed of about 10 to 12 feet per minute while rotating the vibrator shafts *61* at a speed of from about 500 to 1000 R. P. M. and the agitator in the hopper *68* rotating at a speed of from about 25 to 50 R. P. M., the thickness of the adhesive bands deposited upon the strip *M* and the duration and temperature range for drying, curing or vulcanizing the adhesive being determined, as previously set forth, with reference to the type and composition of adhesive employed, the type of fibres used and the character of the bond required according to the particular use which is to be made of the product.

While a particular embodiment of the present invention has been illustrated and described herein, it is not intended to limit the invention to such disclosure, and changes and modifications may be made in and to the apparatus within the scope of the following claims.

I claim:

1. In apparatus for producing pile fibre surfaced strips of material, a device for applying parallel bands of adhesive material upon a continuously moving strip of the material, comprising a fixed support structure, a doctor blade carried by said structure transversely overlying the strip, a bracket disposed crosswise of the strip and mounted for horizontal sliding movement relative to the fixed structure, a plurality of adhesive receptacles on said bracket arranged transversely of the strip, and adapted to abut said doctor blade, and means biasing said bracket toward said fixed structure to maintain said receptacles firmly against said doctor blade.

2. In apparatus for producing pile fibre surfaced strips of material, a device for applying spaced parallel bands of adhesive material upon a continuously moving strip of the material, comprising a fixed support structure, a doctor blade carried by said structure transversely overlying

the strip and adjustable vertically with respect thereto, a plurality of adhesive receptacles arranged in predetermined spaced relation transversely of the strip and adapted to abut against the outer face of said doctor blade, and spring means normally maintaining said receptacles firmly against said doctor blade.

3. In apparatus for producing pile fibre surfaced strips of material, a device for applying spaced parallel bands of adhesive material upon a continuously moving strip of the material, comprising a fixed support structure, a doctor blade carried by said structure transversely overlying the strip and adjustable vertically with respect thereto, a plurality of adhesive receptacles arranged in predetermined spaced relation transversely of the strip, said receptacles each having a declining concave wall portion intermediate side wall portions which project beyond the lower terminal edge of the concave wall and are adapted to abut against the outer face of said doctor blade, and spring means normally maintaining said receptacles firmly against said doctor blade.

4. In apparatus for producing pile fibre surfaced strips of material, a device for applying continuous spaced parallel bands of adhesive material upon a continuously moving strip of the material, comprising a fixed support structure, a doctor blade carried by said structure transversely overlying the strip and adjustable vertically with respect thereto, a bracket disposed crosswise of the strip and mounted for horizontal sliding movement relative to the fixed structure, a plurality of adhesive receptacles carried by said bracket in predetermined spaced relation transversely of the strip, said receptacles each having a declining concave wall portion intermediate side wall portions which project beyond the lower terminal edge of the concave wall and are adapted to abut against the outer face of said doctor blade, and spring means normally biasing said bracket toward said fixed structure to maintain said receptacle side wall portions firmly against said doctor blade.
